CONVERSION OF HYDROCARBON OILS

Jean Delattre Seguy, Chicago, Ill., assignor to
Universal Oil Products Company, Chicago, Ill.,
a corporation of Delaware

Application August 31, 1939, Serial No. 292,881

4 Claims. (Cl. 196—49)

This invention relates specifically to an improved cracking system involving a combination of interdependent steps comprising vapor-phase cracking, reforming and flash distillation which 5 cooperate to produce, from the charging oil and intermediate products of the process, high yields of good antiknock gasoline and minor yields of good quality liquid residue and gases.

One specific embodiment of the invention 10 comprises cracking, in essentially vaporous state, a condensate resulting, as hereinafter described, from fractionation of relatively clean vaporous products of the process, commingling the resulting products with hydrocarbon oil charging stock 15 and with other conversion products of the process, derived as hereinafter described, and separating the mixture into said relatively clean vapors and heavier liquid fractions, fractionating said relatively clean vapors to condense therefrom, 20 as said condensate supplied to the vapor-phase cracking operation, components which contain no substantial quantity of gasoline fractions and have an end-boiling point of the order of 600 to 650° F., further fractionating the uncondensed 25 lighter components of the vapors to form a lighter condensate, consisting essentially of heavy gasoline fractions, and a fractionated vaporous stream consisting essentially of light gasoline fractions of good antiknock value and gases, 30 condensing and recovering said good antiknock light gasoline fractions, separately cracking said lighter condensate under reforming conditions regulated to produce therefrom high yields of full boiling range gasoline of improved antiknock 35 value, separating the products of the reforming operation into liquid and vaporous fractions, separately fractionating the latter to condense therefrom as reflux condensate components boiling above the range of said gasoline of improved 40 antiknock value, supplying said reflux condensate to the same separating zone to which said charging stock and conversion products of the vapor-phase cracking operation are supplied, subjecting fractionated vapors resulting from the last 45 described fractionating step to condensation to form gasoline which is recovered and separated from the uncondensed gases, supplying said liquid fractions derived from the first mentioned separating zone and from the separating zone to 50 which said reformed products are supplied to a reduced pressure distilling zone and therein effecting their appreciable further vaporization, supplying a portion of said uncondensed gases to said distilling zone to assist said distillation, 55 recovering the resulting unvaporized residual liq-

uid, separately cracking the vapors evolved in said distilling zone in the presence of said uncondensed gases supplied thereto and supplying the resulting conversion products to the same separating zone to which said charging stock, said conversion products of the vapor-phase cracking step and said reflux condensate are supplied.

It will be apparent from the above that the various steps of the process are combined in an interdependent and advantageous manner to produce the results above mentioned and the invention is believed to reside in the combination of steps provided, rather than in any individual step of the process. However, the invention also contemplates a process involving less than the 15 entire combination of steps above recited, as there are several such lesser combinations which involve novel and advantageous departures from the prior art and are, therefore, within the scope 20 of the broader aspects of the invention.

The accompanying drawing is essentially a flow diagram of a system incorporating the combination of cooperative steps provided by the invention and in which the above outlined process, as well as various modifications thereof involving 25 less than the entire combination, may be conducted.

Referring to the drawing, the vapor-phase cracking coil 1, to which is supplied a clean condensate of relatively low end-boiling point (say 30 600 to 650° F.), is disposed in furnace 2 and the oil supplied, as will be later described, to this coil is substantially completely vaporized therein and heated during its passage therethrough to the desired cracking temperature. The resulting conversion products are directed from coil 1 through line 3 and valve 4 into separating and fractionating column 5 and preferably are cooled prior to their introduction into the latter zone sufficiently to prevent substantial further cracking 35 thereof. In the case here illustrated, this cooling is accomplished by directly commingling suitable cooling fluid with the conversion products passing through line 3 and may be assisted, when desired, by pressure reduction as the products pass 40 through valve 4 in this line.

I may employ a portion or all of the hydrocarbon oil charging stock for the process as cooling material in line 3 by directing the same from pump 8, to which the charging stock is supplied 50 through line 6 and valve 7, through line 9, line 10 and valve 11 into line 3 and, when desired, reflux condensate recovered from the vaporous products of the reforming operation hereinafter described may be commingled, all or in part, with 55

or without prior cooling, with the vapor-phase conversion products being supplied to the column 5 to serve as cooling material for the latter. The provisions for accomplishing cooling by the latter 5 method will be later described.

The charging stock for the process may be any desired type of hydrocarbon oil ranging from light distillate to crude petroleum, reduced crude or the like and any portion of the charging stock 10 not commingled with the conversion products prior to their introduction into column 5 may be supplied directly to the latter zone at any desired point therein, whereby it is also commingled with the conversion products and assists 15 cooling and fractionation of the latter. Line 12, controlled by valve 13 and communicating with line 9 and column 5, is provided in the case here illustrated for introducing all or any desired portion of the charging oil into the latter zone.

Conversion products of a third cracking step 20 are also supplied to column 5, as will be later described, and the commingled materials supplied to this zone are separated therein into a relatively clean vaporous stream, having an end- 25 boiling point of the order of 600 to 650° F. for example, and heavier liquid fractions. The latter are directed from this zone through line 14 and valve 15 to distilling chamber 16 and the relatively clean vapors are directed from column 30 5 through line 17 and valve 18 to fractionation in fractionator 19.

The vapors supplied to fractionator 19 are partially condensed therein to form the clean condensate supplied as cracking stock to coil 1 35 and the remaining lighter vapors are further fractionated in this zone to form a lighter condensate consisting essentially of heavy gasoline fractions, leaving a fractionated vaporous product which consists essentially of light gasoline 40 fractions of good antiknock value and gases.

The vapor-phase cracking stock is directed from fractionator 19 through line 20 and valve 21 to pump 22 by means of which it is supplied through line 23 and valve 24 to vapor-phase 45 cracking treatment, in the manner above described, in coil 1.

The lighter condensate formed in fractionator 19 is directed therefrom through line 25 and valve 26 to pump 27 by means of which it is supplied through line 28 and valve 29 to reforming treatment in heating coil 30, wherein it is heated to a high cracking temperature at substantial 50 superatmospheric pressure by means of heat supplied from furnace 31, wherein coil 30 is disposed. The cracking conditions employed in coil 30 are regulated to effect reforming of the 55 heavy gasoline fractions supplied thereto (i. e., their conversion into high yields of gasoline of lower initial boiling point and improved anti-knock value).

The reformed products are directed from coil 30 through line 32 and valve 33 into separating chamber 34 and preferably are cooled prior to 60 their introduction into the latter zone sufficiently to prevent their appreciable further cracking and deleterious secondary reactions. This cooling may be accomplished in any well known manner and, in the case here illustrated, provision is 65 made for introducing suitable cooling oil into line 32 through line 35 and valve 35'. Regulated quantities of the vapor-phase cracking stock from fractionator 19 may, when desired, be employed as cooling oil in line 32, this material preferably being removed from line 23 and cooled to

the desired temperature in any well known manner, not illustrated, prior to its introduction into line 32. Provision is also made for utilizing a regulated portion or all of the charging oil to cool the reformed products from coil 30. This is 5 accomplished in the case here illustrated by directing charging oil from line 9 through line 36 and valve 37 into line 32.

Chamber 34 is preferably operated at a substantially reduced pressure relative to that employed at the outlet of coil 30. This reduction in pressure assists cooling of the reformed products and is accomplished as the latter pass through valve 33 in line 32.

In chamber 34 separation is effected between 15 vaporous and heavy liquid components of the commingled reformed products and cooling oil, the liquid components being supplied from this zone through line 36 and valve 37 to distilling chamber 16, while the vapors are directed from chamber 34 through line 38 and valve 39 to fractionation in fractionator 40 wherein their components boiling above the range of the desired gasoline product of the process are condensed as reflux condensate.

The reflux condensate formed in fractionator 40 is directed therefrom through line 41 and valve 42 to pump 43 by means of which it is fed through line 44 and may be supplied therefrom, all or in part, through line 45 and valve 46 into line 3 80 and thence to column 5 or a regulated portion or all of this material may be directed from line 44 through line 47, valve 48 and line 49 into column 5, after commingling in line 49 with relatively 85 hot conversion products of the third cracking step of the system, which will be later described. It is also within the scope of the invention to supply all or any desired portion of the reflux condensate formed in fractionator 40 from line 45 through line 50 and valve 51 directly to column 40 5 without first commingling the same with other conversion products. In order that the reflux condensate from fractionator 40 may function 45 efficiently as a cooling medium in the zone or zones to which it is supplied, it may, when desired, first be passed through cooler 52 and therein cooled to the desired temperature, this being accomplished by closing valve 53 in line 44 and opening valves 55 and 57 in the respective lines 54 and 56 which connect cooler 52 with line 44.

When desired, instead of separating heavy liquid fractions from vapors in chamber 34 the total reformed products from coil 30 and the cooling oil commingled therewith may be supplied directly to fractionator 40, by well known means not illustrated, whereby all the components of these materials boiling above the range of the desired gasoline are included in the reflux condensate formed in fractionator 40, the heavy liquids being subsequently separated therefrom in chamber 5.

The liquid conversion products supplied to chamber 16 from chamber 34 or chamber 5 or both, as the case may be, are appreciably further vaporized in this zone to form a heavier residual liquid product and evolve vaporous fractions suitable for further cracking treatment. Chamber 16 may be operated at a substantially reduced pressure relative to that employed in chamber 5 and/or in chamber 33 to assist vaporization in this zone and, in the preferred embodiment of the invention, vaporization in chamber 16 is also assisted by the introduction thereto of normally gaseous products of the process, as will be later 70 75 80 85 90 95 100 105 110 115 120 125 130 135 140 9515 9520 9525 9530 9535 9540 9545 9550 9555 9560 9565 9570 9575 9580 9585

described. The residual liquid formed in chamber 16 is directed therefrom through line 60 and valve 61 to cooling and storage or elsewhere, as desired, and the vapors evolved in chamber 16, including any normally gaseous fractions supplied to this zone, are directed therefrom through line 62 and valve 63 to pump or compressor 64 wherefrom they are supplied through line 65 and valve 66 to further cracking treatment in heating coil 67.

Coil 67 is disposed in furnace 68, the vapors or mixture of vapors and gases passing therethrough being heated to the desired cracking temperature, preferably at a pressure at least as high as that employed in column 5. When substantial quantities of normally gaseous fractions are included in the materials supplied to coil 67, the conditions employed in the latter zone may be regulated to effect conversion of the gases, as well as the normally liquid fractions, into substantial additional yields of gasoline.

The products formed in coil 67 are directed therefrom through line 69, valve 70 and line 49 into column 5 to commingle therein and undergo separation and fractionation with the charging stock, conversion products from coil 1 and reflux condensate from fractionator 40.

The fractionated vapors which, as aforementioned, consist essentially of low-boiling gasoline fractions and gases, are removed from the upper portion of fractionator 19 through line 71 and valve 72, while fractionated vapors from fractionator 40, which comprise good antiknock gasoline fractions of higher end-boiling point than those removed as vapors from fractionator 19 are removed from fractionator 40 through line 73 and valve 74 and, although these two different boiling range gasolines may, within the scope of the invention be separately condensed and recovered as separate products, they are, in the particular case here illustrated, commingled in line 75 and supplied therefrom to cooling and condensation in condenser 76. The resulting distillate and uncondensed normally gaseous products are directed from condenser 76 through line 77 and valve 78 to collection and separation in receiver 79. The distillate which collects in this zone comprises the final motor fuel product of the process and is directed from the receiver through line 80 and valve 81 to storage or to any desired further treatment.

Gases collected in receiver 79 are discharged therefrom, at least in part, through line 82 and valve 83 to storage or elsewhere, as desired. Preferably, however, a regulated portion of these gases is utilized to assist vaporization in chamber 16 and to accomplish this, provision is made for supplying gases from the receiver through line 84 and valve 85 into chamber 16 to directly commingle in this zone with the liquid products undergoing vaporization therein and assist their vaporization by the partial pressure effect exerted by the gases.

When additional heat is required to obtain the desired vaporization in chamber 16, it may be supplied to this zone by heating the gases, in any well known manner not illustrated, prior to their introduction into chamber 16.

The operating conditions which may be employed to successfully conduct the process of the invention in a system of the character illustrated and above described depend upon the type of charging oil utilized and the market requirements with respect to the characteristics of the products. However, as an example of the operating

conditions which may be employed in most instances, a temperature of the order of 975 to 1200° F. may be employed at the outlet of vapor-phase heating coil 1, preferably with a superatmospheric pressure at this point in the system of the order of 100 pounds, or more, per square inch, the temperature and pressure being correlated to give substantially complete vaporization of the products leaving coil 1. Chamber 5 is preferably operated at substantially the same or somewhat lower pressure than that utilized at the outlet of coil 1 and this pressure may be substantially equalized or reduced in the succeeding fractionating, condensing and collecting equipment. Reforming coil 30 is preferably operated with an outlet temperature of from 925 to 1050° F., or thereabouts, with a superatmospheric pressure measured at the outlet of the coil of from 200 to 1000 pounds, or thereabouts, per square inch. The succeeding separating chamber 34 is preferably operated at a substantially reduced temperature and pressure, the latter ranging, for example, from 30 to 150 pounds, or thereabouts, per square inch and the reformed products preferably enter this zone at a temperature of the order of 750 to 875° F. The pressure employed in chamber 34 may be substantially equalized or reduced in the succeeding fractionating, condensing and collecting equipment. Distilling chamber 16 is preferably operated at a substantially reduced pressure relative to the pressure employed in column 5 and preferably also lower than the pressure employed in chamber 34, the pressure in chamber 16 ranging, for example, from 30 to 100 pounds, or thereabouts, per square inch. Relatively mild cracking conditions are preferably employed in coil 67, the temperature at the outlet of this zone ranging, for example, from 800 to 900° F. when a superatmospheric pressure above 150 pounds or thereabouts, per square inch, is utilized in this zone, while higher temperatures up to 1050° F., or thereabouts, may be utilized with lower pressures. Preferably, the pressure employed at the outlet of this zone is somewhat higher than that utilized in column 5 in order to permit introduction of the heated products from coil 67 to chamber 5 without pumping or compression thereof.

As an example of one specific operation of the process as conducted in a system such as illustrated and above described, the charging stock is a Texas topped crude of approximately 22° A. P. I. gravity which is supplied, in part, to transfer line 32 leading from reforming coil 30 to chamber 33 and, in part, to column 5. The temperature employed at the outlet of coil 1 is approximately 1100° F. with a pressure at this point in the system of about 75 pounds per square inch. Substantially the same pressure is utilized in column 5 and the vaporous stream supplied from the latter zone to fractionator 19 has an end boiling point of about 650° F. The condensate supplied from fractionator 19 to coil 1 has the same end-boiling point and contains over 90% of the fractions boiling between 400 and 600° F. The overhead vaporous stream removed from fractionator 19 has an end-boiling point of approximately 275° F. and the condensate supplied from fractionator 19 to reforming coil 30 has an end-boiling point of approximately 450° F. and contains over 95% of the fractions boiling above 250° F. The temperature employed at the outlet of reforming coil 30 is approximately 1000° F. with a superatmospheric pressure at this point in the system of about 300

pounds per square inch. The pressure employed in chamber 34 is reduced to approximately 90 pounds per square inch and the temperature of the reformed products entering the latter zone 5 is reduced to approximately 870° F. Fractionator 40 is also operated at a superatmospheric pressure of approximately 90 pounds per square inch and the reflux condensate in this zone is cooled and commingled, in part, with the stream 10 of heated products passing from coil 1 to column 5 and, in part, to the stream of heated products passing from coil 67 to column 5. The end-boiling point of the overhead vaporous stream removed from fractionator 40 is approximately 15 400° F. Chamber 16 is operated at a superatmospheric pressure of about 30 pounds per square inch and gases from receiver 19 are supplied to this zone to assist vaporization therein, the receiver being operated at a superatmospheric pressure 20 of about 55 pounds per square inch. The temperature employed at the outlet of coil 67 is approximately 975° F. with a superatmospheric pressure at this point in the system of about 100 pounds per square inch. 25 The above described operation will yield per barrel of charging stock approximately 51% of 400° F. end-point gasoline which is a blend of the gasolines recovered from the fractionated vaporous stream from fractionator 19 and the 30 fractionated vaporous stream from fractionator 40. Approximately 22% based on the charging stock of liquid residue, having good fuel oil characteristics, is produced and the remainder of the charging stock is accountable for as uncondensed 35 gases.

I claim as my invention:

1. A hydrocarbon oil cracking process which comprises reforming a light condensate, derived as hereinafter set forth and consisting essentially 40 of heavy gasoline fractions, under thermal cracking conditions regulated to produce therefrom high yields of gasoline of lower initial boiling point and improved antiknock value, separating from the products of the reforming operation a 45 fractionated vaporous stream consisting essentially of said improved antiknock gasoline and gas, condensing said gasoline and separating the same from the uncondensed gases, separating selected heavier liquid components from the reformed products and commingling the same with at least a portion of the hydrocarbon oil charging 50 stock for the process and with other con-

version products of the process derived as hereinafter set forth, separating the resulting mixture into a relatively clean vaporous stream and a stream of heavier liquid fractions, substantially vaporizing the latter in a zone of reduced pressure relative to that at which the last mentioned separation is effected, whereby to form additional vapors and heavier, non-vaporous residue, separately cracking said additional vapors and commingling resulting conversion products, as aforesaid, with said selected heavier liquid components of the reformed products, fractionating said relatively clean vapors to form a clean condensate substantially devoid of gasoline, a lighter condensate consisting essentially 15 of heavy gasoline fractions and comprising the oil subjected to said reforming, and a vaporous stream consisting essentially of gas and good antiknock, light gasoline fractions of lower end boiling point than said gasoline recovered from 20 the reformed products, condensing said light gasoline and separating the same from the uncondensed gas, separately cracking said clean condensate in essentially vaporous state and commingling resulting products, as aforesaid, with 25 said selected heavier liquid components of the reformed products.

2. The process defined in claim 1 wherein hydrocarbon oil charging stock for the process is commingled with the reformed products prior 30 to the separation therefrom of said selected heavier liquid components, whereby to include at least a portion of said charging oil therein.

3. The process defined in claim 1 wherein hydrocarbon oil charging stock for the process is commingled with the reformed products prior to separation of their vaporous and liquid components, and wherein a liquid fraction, heavier than said selected liquid components of the reformed products and including heavy fractions 40 of the charging stock, is separated from the mixture of charging oil and reformed products and supplied to said zone of reduced pressure vaporization.

4. The process defined in claim 1 wherein a 45 portion of said uncondensed gases is introduced into said zone of reduced pressure vaporization to assist vaporization therein and commingled with said additional vapors supplied to the second mentioned cracking step.

JEAN DELATTRE SEGUY.
